CLAIM

The ornamental design for an end cap for an endoscope, as shown and described.

DESCRIPTION

FIG. 1 is a front, top, and, right side perspective view of an end cap for an endoscope showing my new design;

FIG. 2 is a top perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a cross-sectional view taken along line 9-9 in FIG. 7;

FIG. 10 is a cross-sectional view taken along line 10-10 in FIG. 7;

FIG. 11 is a cross-sectional view taken along line 11-11 in FIG. 7;

FIG. 12 is a front, top, and right side enlarged perspective view of a raising stand and other interior mechanism elements thereof; and,

FIG. 13 is a rear, top, and left side enlarged perspective view of a raising stand and other interior mechanism elements thereof.
